MOVIE PROJECTOR CABINET

Louis Glaser, 1216 Main St., Columbia, S.C.

Filed Aug. 12, 1960, Ser. No. 61,720

Term of patent 3½ years

(Cl. D61—1)

Fig.1

Fig.2

Fig.3

Fig.4

Fig. 1 is a perspective view of a movie projector cabinet, showing my new design;
Fig. 2 is a rear elevational view thereof;
Fig. 3 is a top plan view; and
Fig. 4 is a side elevational view of the same.

I claim:
The ornamental design for a movie projector cabinet, as shown.
